ELECTRIC SWITCH CONTROL MEANS

Arthur Binns, Soho Foundry, Birmingham,
England, assignor to W. & T. Avery Limited,
Soho Foundry, Birmingham, England

Application September 26, 1938, Serial No. 231,741
In Great Britain September 30, 1937

2 Claims. (Cl. 200—52)

This invention has reference to improvements relating to electric switch control means particularly for use with weighing mechanism, the invention having for its primary object the provision of an improved electric switch control unit which is simple and effective in operation and which is capable of being adapted for the control of a wide variety of electrically operated auxiliary apparatus employed in conjunction with weighing mechanism.

The invention consists of an improved electric switch control means wherein the electric switch is associated with a member which normally tends to move the switch to the circuit making position and wherein the completion of the circuit by the switch energises an electro-magnetic device which tends to influence the said member so as to restore the switch to the circuit breaking position, and wherein the actuation of the said member to move the switch to one or other of the aforesaid positions is restrained by locking devices one or other of which is moved out of the locking position as required by a movable element associated with the mechanism which is required to be controlled by the switch.

The invention further resides in the details of construction of the improved switch control mechanism to be described hereinafter.

A preferred embodiment of the present invention will now be described in its application to a switch control mechanism for the electrically operated totalising apparatus for use with weighing mechanism as described in the specification of patent application Serial No. 104,249 dated October 6, 1936.

The invention is illustrated by the accompanying drawings, wherein similar reference numerals indicate similar parts in the several views.

Figure 1 is a front elevation of the mechanism comprising the present invention showing the parts in the position occupied when the circuit through the electrically-operated totalising apparatus is broken.

Figure 2 is a similar elevation to that seen in Figure 1, but illustrates the position of the parts when the circuit through the electrically operated totalising apparatus is closed.

Figure 3 is a part sectional plan on the line 3—3 of Figure 2.

According to this embodiment of the invention the circuit from the supply mains to the electric motor for driving the totalising apparatus includes a tiltable mercury switch 4 which is connected by straps 4^a to a lever 5 which lever normally tends to move the switch 4 into the circuit

making position (Figure 2) under the action of gravity. This lever 5 is fulcrumed on the pin 6 and is connected intermediate its ends by means of a pin 7 to the lower end of the moving core armature 8 of an electro-magnet 9 which is incorporated in the aforesaid circuit through the tiltable mercury switch 4 by means of the leads 9^a, so that whenever the switch 4 completes the circuit the electro-magnet 9 is energised, and tends to cause the armature 8 through the lever 10 to restore the switch 4 to the circuit breaking position seen in Figure 1. The electro-magnet 9 operates with a time lag in order to ensure the efficient operation of the several components of the control means as will appear from the statement of operation of the invention which follows in the specification.

The switch-carrying lever 5 is provided intermediate its ends with an outwardly cranked plate 10 carrying a pin 10^a on which is mounted a roller 11. This roller is adapted to co-operate with two levers 12 and 13 respectively the lever 12 is fulcrumed on the pin 12^a, and is counterweighted by means of the weight 12^b and is so positioned that the arm 12^c of this lever normally supports the roller 11 as seen in Figure 1, thereby maintaining the switch carrying lever 5 in the raised position seen in this figure. The lever 13 is fulcrumed on the pin 13^a and is formed as a bell-crank the arm 13^b thereof is adapted to bear against the said roller 11 and constitutes a holding-down device for the switch-carrying lever 5 when this lever is tipped to its lowest position as seen in Figure 2 as will be hereinafter explained.

A fixed stop 14 is provided to limit the upward motion of the lever 5, while a fixed stop 15 is provided to limit the downward motion of the lever 12, and adjustable stops 16, 16^a are provided the stop 16 serving to limit the upward motion of the lever 12, and the stop 16^a the downward motion of the lever 13.

Mounted on the weighing lever 17 are a pair of adjustable stops 18, 18^a, the stop 18 being associated with the resilient spring plate 19 which is secured at one end to the lever 17.

The operation of the invention is as follows:

Normally the lever 5 carrying the mercury tube tiltable switch 4 occupies the position seen in Figure 1, in which position the circuit through the driving motor for the totalising apparatus of the 50 weighing mechanism is broken, this position being determined by the contact of the upper edge of the lever 5 with the underside of the projecting stop pin 14, and the fact that the roller 11 associated with the lever 5 is supported by the sharp 55

extremity of the arm 12^c of the lever 12. Assuming now that a load is applied to the lever system of the weighing mechanism then the short arm of the lever 17 falls and in so doing through the 5 contact of the adjustable stop 18 and the flexible strip 19 pressure is applied to the pin 12^d projecting from one arm of the lever 12, thereby turning this lever and removing the support of the arm 12^c from beneath the roller 11, thus permitting 10 the lever 5 to fall to the position seen in Figure 2, which results in the tipping of the mercury switch 4 and the closing of the circuit through the electro-magnet 9. During this circuit-closing operation the roller 11 on the lever 5 is bearing 15 against one edge of the arm 13^b of the bell-crank lever 13 with the result that when the lever 5 reaches its lowest position the pointed end of the arm 13^b passes over the top of the roller 11 and serves as a holding-down device for the 20 lever 5 against the attractive force generated by the energisation of the electro-magnet 9, this holding-down position of the bell-crank lever 13 being determined by the position of the adjustable stop 18^a. The counter-weighted lever 12 is carried 25 to the position seen in Figure 2 by the contact of the flexible strip 19 with the pin 12^d and the lever is maintained in this position by the pressure exerted by the pin 5^a projecting from the lever 5 upon the upper edge of the lever 12 30 which is limited in its downward movement by the fixed stop pin 15.

Assuming now the load is removed from the weighing apparatus the short arm of the lever 17 moves upward and in so doing the adjustable 35 stop 18^a strikes the laterally projecting pin 13^c of the bell-crank lever 13 thereby releasing the arm 13^b from its holding-down position relative to the roller 11 and permitting the attractive force 40 of the electro-magnet 9 through the armature 8 raising the lever 5 to its circuit breaking position as seen in Figure 1. At the same time the upward movement of the short arm of the lever 17 frees the counterweighted lever 12 so as to permit 45 this lever under the action of the weight 12^b to swing back to the position seen in Figure 1, when the pointed end of the arm 12^c of this lever is again positioned under the roller 11 to definitely support the lever 5 and thus maintain the tilt- 50 able switch 4 in the circuit-breaking position, the upward or return motion of the counterweighted lever 12 being limited by its contact with the adjustable stop 16. The mechanism is now reset for a subsequent operation.

It will be appreciated that by the employment 55 of the counterweighted control lever 12 and the bell-crank lever 13 that the switch-carrying lever 5 is positively maintained either in its upper or

in its lower position according to requirements irrespective of the normal gravitational action of the lever 5 and of the attractive force which is applied to this lever through the electro-magnet 9, so that there may be said to be a positive holding-up of the lever 5 by the lever 12 and a positive holding-down of the lever 5 by the bell-crank lever 13 independent of the force of gravity or of the return or counter-operative force which are associated with this lever through the electro-magnet 9 as has been explained.

What I claim is:

1. An electric switch control means, comprising a switch of the mercury tilttable type, an overhanging lever supporting said switch, which lever normally tends, under the force of gravity, to move the switch to the circuit making position, an electro-magnetic device coupled to said lever energised upon the completion of a circuit operating to return the lever to its circuit breaking position, and a pair of locking levers one adapted to positively support the said switch carrying lever in its raised or circuit breaking position, and the other adapted to positively hold the switch carrying lever down in its circuit making position, said pair of levers co-operating with a movable element of a weighing system whereby each of the said pair of locking levers in turn is positively tripped to release the switch carrying lever.

2. An electric switch control means associated with a weighing mechanism, comprising a tilttable mercury switch, an overhanging lever on which said switch is mounted, normally operating under the force of gravity to maintain the said switch in the circuit closing position, an electro-magnetic device coupled to the said lever normally tending upon the completion of the circuit through the said device to restore the lever to the circuit breaking position, a counterweighted lever adapted to co-operate with a roller mounted on the switch carrying lever to maintain the said lever in its circuit breaking position, and a bell crank lever adapted to co-operate with the said roller to maintain the switch carrying lever in the circuit making position, the said counter-weighted lever and the bell crank lever both being adapted for positive operation by means of a movable element in the weighing system for the purpose of alternatively tripping the said levers so as to free the switch carrying lever and to permit of its performing its normal operation in one direction under the force of gravity, and in a converse direction under the attractive influence of the electro-magnetic device, and stops limiting the movements of the said levers.

ARTHUR BINNS.
